UNITED STATES PATENT OFFICE.

SAXTON S. BARRETT, OF CHICAGO, ILLINOIS; THE NORTHERN TRUST COMPANY, EXECUTOR OF SAID SAXTON S. BARRETT, DECEASED, ASSIGNOR TO MARY K. BARRETT, OF GLENCOE, ILLINOIS.

TEMPORARY BINDER.

1,109,028.

Specification of Letters Patent.

Patented Sept. 1, 1914.

Application filed May 10, 1912. Serial No. 696,364.

To all whom it may concern:

Be it known that I, SAXTON S. BARRETT, a citizen of the United States, residing at Chicago, in the county of Cook and State 5 of Illinois, have invented certain new and useful Improvements in Temporary Binders, of which the following is a specification, reference being had to the accompanying drawings.

10 My invention relates to temporary binders, and has for its object to provide a new and improved binder for newspapers of such construction that the papers may be readily applied to and removed therefrom 15 and by which they may be securely held in position. I accomplish this object as illustrated in the accompanying drawings and as hereinafter described.

What I regard as new is set forth in the 20 claims.

In the accompanying drawings,—Figure 1 is a side view of my improved binder; Fig. 2 is a longitudinal vertical section thereof, partly broken away; Fig. 3 is a perspective 25 view of one of the retaining strips; Fig. 4 is a cross-section on line 4—4 of Fig. 2, looking to the left; Fig. 5 is a cross-section on line 4—4 of Fig. 2, looking to the right; Fig. 6 is a cross-section of the intermediate 30 portion of the binder, as on line 6—6 of Fig. 2; Fig. 7 is a cross-section on line 7—7 of Fig. 2; and Fig. 8 is a perspective view of the securing device for the retaining strips.

35 Referring to the drawings,—9 indicates a rod of wood or other suitable material which forms the main portion or hub of the binder and supports the retaining strips and securing devices therefor. Said hub is 40 provided with longitudinal grooves 10 arranged at intervals around it, as shown in Fig. 6, forming intermediate radial shoulders 11. One or both ends are provided with hand-pieces 12, as shown in Fig. 1.

45 13 indicates a number of retaining strips for securing the newspapers to the hub, said strips being preferably of metal. At one end the retaining strips are secured to an end portion of the hub 9 by means of a 50 circular rod or ring 14 which is secured to the hub in any suitable way, as by a nail 15, as shown in Fig. 7. The ring 14 intersects the several grooves 10 and lies about midway of said grooves, as shown in Fig. 7.

The several retaining strips are pivoted 55 upon the ring 14 so that their free ends may swing toward and from the hub and so that they are capable of lateral movement upon the ring within the confines of their respective grooves. Near the opposite end of 60 the hub I provide a securing device 16 in the form of a ring-plate having in its periphery a series of hooks 17 and slots 18, narrow 65 passages 19 being provided between the several hooks and the adjacent portions of the ring-plate for the passage of the retaining strips, as shown in Figs. 5 and 8. The securing device 16 is placed adjacent to one 70 of the handles 12, as shown in Fig. 2 and is secured in position in any suitable way. This is best accomplished by cutting down 75 one end portion of the hub 9 to form a tongue and fitting the ring-plate 16 upon said tongue so that it abuts against the shoulder thus formed and then fitting the handle 12 upon the tongue so that the ring-plate 16 lies between the handle and the grooved portion of the hub 9, as shown in Fig. 2. The handle is provided with suitable recesses 19^a to receive the ends of the 80 securing strips, as shown in Figs. 1 and 2.

20 indicates a finger-piece with which each retaining strip 13 is provided, to facilitate operating it.

From the foregoing description it will be 85 seen that when the newspaper is placed upon any retaining strip and the retaining strip is secured to the ring-plate by carrying it down through the passage 19 into engagement with one of the hooks 17, the fold of 90 the newspaper will lie in the groove 10 and will, therefore, be held against lateral shifting, although the turning of the leaves of the newspaper is not interfered with. As many newspapers may be placed in the 95 binder as can be accommodated by the number of retaining strips provided; and by reason of the lateral adjustment of the several retaining strips permitted by hinging them in the manner described they may adjust 100 themselves to the newspaper, whether the retaining strip be placed in the center fold or not, so that where the pages of a newspaper are pasted together it is not essential that they be placed in the binder so 105 that the retaining strip engages the center fold.

As shown in Fig. 8, the slots in the se-

curing device for the retaining-strips have inclined entering passages designed to twist the retaining-strips as they are moved into or out of said slots, the hinged ends of said retaining-strips being held against twisting by the rod on which they are mounted,— the purpose of this arrangement being to prevent accidental disengagement of the retaining-strips from the securing devices. I do not, however, wish to be limited to this construction, as any other suitable type of slot may be employed, as, for example, slots of the type shown and described in my application for patent for temporary binder of even date herewith, Serial No. 696,361.

The number of retaining-strips provided may, of course, be varied, although ordinarily for newspaper purposes it is desirable that seven be provided.

The retaining-strips may be made of any suitable material, but are best made suffi-

ciently elastic so that they may spring out between their ends, as may be necessary to accommodate newspapers of different thicknesses.

25

That which I claim as my invention, and desire to secure by Letters Patent, is,—

A temporary binder, comprising a hub having a series of longitudinal grooves arranged at intervals around it, a series of retaining strips pivotally connected with said hub and adapted to lie in said grooves, a series of securing hooks adapted to engage and secure the free ends of said retaining strips, and a handle connected with said hub, said securing hooks being placed between the handle and a portion of the hub.

SAXTON S. BARRETT.
